(57) **CLAIM**

The ornamental design for a shield, as shown and described.

DESCRIPTION

FIG. 1 is a perspective view of a first embodiment of a shield;

FIG. 2 is a front view thereof;

FIG. 3 is a rear view thereof;

FIG. 4 is a right view thereof;

FIG. 5 is a left view thereof.

FIG. 6 is a top view thereof; and

FIG. 7 is a bottom view thereof.

FIG. 8 is a perspective view of a second embodiment of a shield.

FIG. 9 is a front view thereof.

FIG. 10 is a rear view thereof.

FIG. 11 is a right view thereof.

FIG. 12 is a left view thereof.

FIG. 13 is a top view thereof; and,

FIG. 14 is a bottom view thereof.

The broken lines depict portions of the shield that form no part of the claimed design.

1 Claim, 14 Drawing Sheets
